UNITED STATES PATENT OFFICE.

ERWIN A. GEIGER, OF RIDGEWOOD, NEW JERSEY, AND AUGUST F. SCHRAEGLE, OF RIDGEWOOD, AND HENRY T. JENNINGS, OF GLENDALE, NEW YORK, ASSIGNORS TO RAPID ADDRESSING MACHINE COMPANY, A CORPORATION OF NEW YORK.

EXTENSIBLE PEDAL CONNECTION FOR ADDRESSING MACHINES.

Application filed July 1, 1926. Serial No. 119,826.

This invention relates generally to automatic means for tripping the driving clutch of a power-driven mechanism and means under control of the operator for afterwards resetting the same so that the machine may continue in operation until the clutch is again automatically thrown out. More specifically it embodies an improvement on the invention described and claimed in our 10 U. S. Patent No. 1,518,912, granted December 9, 1924, and is herein illustrated in the form in which it has been applied to an addressing machine of the type covered by U. S. Patent No. 1,256,509 granted to E. D. 15 Belknap, February 19, 1918.

Our present improvement embodies one device for overcoming the noise and jar created in the operation of certain previously patented apparatus of this general character by inserting an extensible connection from the pedal system to the clutch throw-out mechanism and having the automatic selecting device (not shown) permit this connection to be extended when one of the pre-determined class of cards is fed out of the magazine to printing position, the pedals remaining locked in depressed position until released by the operator. One form of apparatus embodying our present invention is 20 illustrated in the attached three sheets of drawings, in which,

Fig. 1 is a side elevation of the pedals and their connections, parts being shown in section, and others broken away,

Fig. 2 is a plan view.

Fig. 3 is an elevation of the extensible connecting rod on a larger scale to illustrate its mode of operation, and

Fig. 4 is a section on line 4—4 of Fig. 1. 40 Throughout the drawings like reference characters indicate like parts. 1, 1, are the uprights of the main frame of the machine supporting a table carrying the operating parts such as the card handling, printing and selective mechanism, (not shown), said uprights being held together by side bars, one of which is shown at 3, and cross bars such as 2 and 23 shown broken away. 45 10 (Fig. 1) represents diagrammatically a clutch on the main driving shaft of the machine which is usually of the one revolution type, being automatically thrown out at the end of each cycle of operation of the ma-

chine by the throw-out cam 72 when the latter is swung up on its pivot 73 by the spring 55 74 into the position shown in full lines in Fig. 1. 17 is a pedal rigidly mounted on the bent crank shaft 18, pivoted on the side bars 3, at 18^a (Fig. 2), and connected by an extensible connecting rod 6—16 to the throw-out cam 72. This connecting rod or link is of a telescoping character, the lower portion 6 being connected to the upper portion 16, by a pin and slot arrangement consisting of the pin 11, screwed into the connecting rod section 16, and engaging slot 9 in the connecting rod section 6. These two rod sections 6 and 16 are held in non-extended position shown in full lines in Figs. 3 and 4 by the hook-shaped latch 12 pivoted at 13 on 60 the upper link section 16, and normally engaging the pin 14 on the lower link section 6. The upper end of the latch 12 is widened out into sector shape and provided with a spring-pressed ball or plunger 21, adapted 65 to engage either one of the recesses 21^a, or 21^b, in the latch holder 22, screwed to the upper link section 16 and located in the plane of said latch, as best shown in Fig. 4. Obviously, when the latch 12 is in the position shown in full lines in Fig. 3 with the ball 21 engaging the notch 21^a, and the hooked end of the latch engaging pin 14, the telescoping link 6—16 is held in non-extended 70 condition and moves as a unit when pedal 17 is pressed downward, thereby pulling down the throw-out cam 72 and permitting the clutch 10 to remain in engagement. This permits clutch 10 to drive the machine continuously. If, however, while said pedal 17 75 is held in depressed position, the latch 12 is rotated in clockwise direction so that its hooked end clears pin 14, the spring 74 will pull up the throw-out cam 72 and the upper section 16 of the extensible connecting rod, 80 which is pivoted to 72, as far as the movement of the pin 11 in slot 9 permits, and the driving clutch 10 will be thrown out of engagement at the expiration of that cycle of the machine operations, the link section 16 85 and latch 12 then assuming the dotted line position shown in Fig. 3.

The particular apparatus for thus freeing latch 12 from pin 11 here illustrated comprises the link 26 pivoted at 15 to the upper 90 portion of the latch and at its other end piv-

oted to the core 27 of the solenoid 28. Obviously, when this solenoid is energized by the passage of an electric current through its coils, the core 27 will be pulled inward and the latch 12 swung into dot and dash line position, permitting the extensible connecting rod 6-16 to be elongated by lifting the section 16 and the latch 12 into the dotted line position and the machine stopped as previously described.

If, after the connecting rod has been thus elongated, the pedal 17 is permitted to rise, latch 12 can be caused to reengage pin 14 and thus hook up the connecting rod sections 6-16 in non-extended position so that when pedal 17 is again depressed, cam 72 will be also pulled down and clutch 10 will be allowed to go into mesh and the machine will start running again.

The apparatus for thus relatching connecting rod 6-16 in shortened condition here illustrated comprises the link 26^a, one end of which is pivoted at 15^a to the upper portion of latch 12, while its other end is pivoted at 37 to the crank arm 36 on sleeve 35 which is loosely mounted on cross bar 23 of the main frame, which cross bar is of cylindrical shape, said sleeve 35 having operative connections to reset pedal 29, also pivoted on cross bar 23. The preferred form of operating connections between pedal 29 and sleeve 35 comprises a second sleeve 30 to which pedal 29 is rigidly connected and which is also loosely mounted on shaft 23 and provided with a projecting lug 38 co-operating with lug 40 projecting from the adjacent end of sleeve 35. Obviously, when pedal 29 is pressed downward and lugs 38 and 40 are in contact, the rotation of sleeve 30 will be transmitted to sleeve 35, and link 26^a will be pulled to the left (looking at Fig. 1), thus slightly rotating latch 12 in a counterclockwise direction back into the full line position shown in Fig. 3. This will pull out solenoid core 27 into the position shown in Fig. 1, cause the latch to engage pin 14 (assuming that pedal 17 is in raised position), and reset the parts with the connecting rod 6-16 in non-extended position so that when pedal 17 is again depressed the main clutch will be disengaged and the machine again started into operation.

In a machine organized to run continuously until the selective apparatus or other automatic device trips the latch 12 and stops the machine, it may be desirable to provide means for locking the pedal 17 in depressed position so that the operator need not hold his foot upon it or otherwise positively maintain it in depressed position by continuous effort. In the apparatus described this is accomplished by the swinging lock member 20 carried by sleeve 30 and adapted to engage a lug 41 on pedal 104 which is pivoted at 105 to pedal 17 and overhangs the

laterally projecting stud 106 carried by pedal 17. This pedal 104 (called the skip pedal in machines of this character), when depressed, carries down with it pedal 17 and, so long as lock 20 is in line with lug 41, will be held by 20 in depressed position and also hold down pedal 17, thus permitting the machine to run on. When, however, the operator presses down on reset pedal 29, he will swing lock 20 out of line with lug 41, as shown in full lines in Fig. 1, and thereupon spring 7 (Fig. 2), which is anchored on bent cross bar 2 of the main frame and at its lower end connected to pedal 17, will raise said pedal 17, telescoping connecting rod 6-16 back into shortened position ready for re-engagement of latch 12 with pin 14, which latch is simultaneously swung into such re-engagement with said pin by the same or continued movement of reset pedal 29 through the train of connecting mechanism terminating in link 26^a as before explained. Upward motion of the pedal 17 also carries up skip pedal 104 through the action of stud 106.

Spring 19 connected at its upper end to the crank arm 39 on sleeve 30, and at its lower end to skip pedal 104, tends to rotate sleeve 30 in a clockwise direction, (looking at Fig. 1) whenever skip pedal 104 is depressed, with the result that as soon as lug 41 on said pedal gets below the lower end of swinging lock 20, the latter is snapped over into dotted line position shown in Fig. 1, so that when the operator thereafter moves his foot from pedal 104 it is still held down by lock 20.

Lock 20 is prevented from swinging too far in this resetting operation and is held in position to register with lug 41 by lug 34 on the under side of sleeve 30 striking against lug 33, carried by stop collar 31 held in adjusted position on shaft 23 by thumbscrew 32. Collar 31 also prevents sleeve 30 from sliding on the shaft 23 away from sleeve 35, and sleeve 35 is held against motion in the opposite direction by collar 42.

107 is a link pivoted by screw pin 25 to skip pedal 104 and operating a card skipping mechanism, not shown, but similar to that described in our before mentioned patent.

The lower section 6 of the extensible connecting rod 6-16 is fastened on the lever of pedal 17 by screw 5 and pins 8-8.

Operation of our invention when applied to an addressing machine of the type described in our before mentioned patent, and here shown in part, is as follows: The selective device is set so as to be actuated by any one of a class of stencil cards with which it is desired to effect a printing operation. The machine is then started by pressing down the skip pedal 104 which will carry with it the printing pedal 17 and throw the

apparatus controlled by link 107 into a position which will disable the printing apparatus. Both pedals will be held down by lock 20 which is swung by spring 19 into dotted line position shown in Fig. 1 to engage lug 41 on pedal 104. This also raises reset pedal 29 into dot-and-dash line position, but, as lug 38 then simply moves away from lug 40, no motion is transmitted to sleeve 35 and latch 12 is allowed to remain in its engaged position so that connecting rod 6-16 is held in telescoped or non-extended condition and cam 72 is thereby held down out of operative position by pedal 17 as shown in dot-and-dash lines in Fig. 1. This leaves clutch 10 free to engage and the machine runs on, feeding and skipping all stencil cards, until another one of the class to be used in printing reaches printing position. Thereupon the selective mechanism energizes solenoid 28, latch 12 is tripped, spring 74 pulls cam 72 up into operative position, and the clutch 10 is disengaged at the end of that cycle, leaving that stencil card in printing position. The operator then presses down reset pedal 29, which frees lock 20 from lug 41, permitting skip pedal 104 and also printing pedal 17 to rise under the pull of springs 7 and 19. The tripping of latch 12 by its clockwise movement, above described, has also given a clockwise movement to sleeve 35 and moved lug 40 over into contact with lug 38. Consequently the above described depression of reset pedal 29, producing a counter-clockwise rotation of sleeve 30, has also produced a similar slight rotation of sleeve 35 sufficient to cause latch 12 to re-engage pin 14, which is now possible as the lower section 6 of the extensible connecting rod has risen with pedal 17. The connecting rod 6-16 being thus hooked up in contracted condition, the operator now presses down printing pedal 17 for a moment, thus withdrawing cam 72 and permitting the machine to operate through one cycle, printing from and expelling the stencil card which has been selected for this purpose by the selective apparatus in the previously described operations. The pressure on pedal 17 should only be momentary so that cam 72 may rise again and be in position to stop the machine at the end of that cycle. After the printing operation the operator again presses down skip pedal 104, resetting lock 20 and starting the machine again on its operation of feeding and skipping cards until another card of the class to be used in printing is fed into printing position and latch 12 has been again tripped by the selective apparatus in the manner first described.

The main advantage of this invention arises from the fact that the stoppage of the machine is effected by the selective device through the movement of only the small, light-weight parts 16 and 72, and without

the creation of any objectionable noise or shock of heavy moving parts. It is only after the operator has depressed reset pedal 29 that pedals 104 and 17 are allowed to rise, and any shock which might then be caused by a sudden stoppage at the upper limit of their movements can be avoided by the operator holding his other foot over pedal 104 so as to cushion this upward movement.

While we have shown and described our invention as applied to an addressing machine of the particular type above referred to, it is evident that modified forms of the invention might be applied to other forms of addressing machines and to other classes of power-driven mechanism wherever it is desirable to automatically stop the same without producing objectionable noise and shock, and this can be done without departing from the underlying principle of our invention as the same has been set forth in certain of the appended claims.

Having described our invention we claim:

1. A device for automatically controlling a throw-out clutch for power-operated driving mechanism which device comprises, in combination, a clutch controlling member, yielding means normally tending to lift said member into position to throw out the clutch, a pedal, a connection to said clutch controlling member from said pedal, which connection is extensible, and means permitting an extension of said connection; whereby said clutch controlling member may be permitted to rise and throw out said clutch while said pedal is still in depressed position.

2. A combination, such as defined in claim 1 in which said extensible connection comprises a telescoping connecting rod, and a hook pivoted on one member of said telescoping connecting rod and cooperating with engaging means on the other member thereof.

3. A combination, such as defined in claim 1 in which said extensible connection comprises a telescoping connecting rod, and a hook pivoted on one member of said telescoping connecting rod and cooperating with engaging means on the other member thereof, together with mechanism for automatically swinging said hook so as to free it from said engaging means.

4. A combination, such as defined in claim 1 in which said extensible connection comprises a telescoping connecting rod, and a hook pivoted on one member of said telescoping connecting rod and cooperating with engaging means on the other member thereof, together with electrically operated mechanism for automatically swinging said hook so as to free it from said engaging means.

5. The combination of a movable member, yielding means normally tending to move

said member in one direction, a movable element under control of the operator, an extensible connection to said member from said movable element, an automatically operated device permitting extension of said connection while under stress exerted between said movable member and, said movable element, and mechanism under control of the operator for relocking said connection in non-extended condition after such stress has been removed.

6. A combination such as defined in claim 5 in which said extensible connection comprises a telescoping connecting rod, and said locking means comprises a hook pivoted on one portion of said telescoping rod and adapted to temporarily engage the other member.

7. A combination such as defined in claim 5 in which said extensible connection comprises a telescoping connecting rod, and said locking means comprises a latch pivoted on one portion of said telescoping rod and adapted to temporarily engage the other member, and in which said relocking mechanism comprises a pedal operatively connected to said latch.

8. In a power-driven apparatus the combination, with driving means therefor, of a device adapted to disconnect said apparatus from said driving means, a pedal, a telescoping link connected at one end to said pedal and at the other to said disconnecting device, means for temporarily holding said link in telescoped condition, locking mechanism adapted to temporarily hold said pedal in depressed position, whereby said disconnecting device is held out of operation as long as said link remains in telescoped condition, automatic apparatus for releasing said means holding said link in telescoped condition, whereby said link may be extended and said disconnecting device thereby thrown into action while said pedal is still depressed, and a second pedal adapted, when depressed, to both free said locking mechanism, thereby allowing said first pedal to rise and telescope said link, and to re-establish in engagement the means for temporarily holding it in such telescoped condition.

9. A combination such as defined in claim 8 in which said means for temporarily holding said link in telescoped condition comprises a hook pivoted on one element and engaging a projection on the other element of said telescoping link, and in which said second pedal is connected to said hook through a rotating sleeve carrying a crank to which is pivoted a link also pivoted to said hook.

10. A multiple pedal apparatus for controlling the operation of a power driven machine, which apparatus comprises the combination of a power disconnecting de-

vice, a pedal, a telescoping connecting rod constituting a connecting element between said device and pedal, whereby the power may be connected to the machine when and while said pedal is depressed, detachable means for holding said connecting rod in telescoped condition, a lock for holding said pedal in depressed position, apparatus for detaching said holding means, whereby the power may be disconnected while said pedal is still depressed, and a second pedal adapted to trip said lock, and also to reattach said holding means after said connecting rod has been shortened by the rising of said first mentioned pedal.

11. A combination such as defined in claim 10 in which said lock for holding said first mentioned pedal in depressed condition comprises a member rigidly connected to said second pedal and adapted to engage said first mentioned pedal when the latter is depressed and the former is in raised position.

12. A combination such as defined in claim 10 in which said lock for holding said first mentioned pedal in depressed condition comprises a member connected to said second pedal and adapted to engage said first mentioned pedal when the latter is depressed and the former is in raised position, together with a spring normally tending to force said lock into, and hold it in, engagement.

13. A combination such as defined in claim 10 in which said detachable means for holding said connecting rod in telescoped condition comprises a movable member mounted on one section of said rod and adapted to engage the other section when said rod is telescoped.

14. A combination such as defined in claim 10 in which said detachable means for holding said connecting rod in telescoped condition comprises a movable member mounted on one section of said rod and adapted to engage the other section when said rod is telescoped, and in which said apparatus for detaching said holding means comprises a train of mechanism extending from said movable member to said second pedal.

15. A combination such as defined in claim 10 in which said detachable means for holding said connecting rod in telescoped condition comprises a movable member mounted on one section of said rod and adapted to engage the other section when said rod is telescoped, and in which said apparatus for detaching said holding means comprises a train of mechanism extending from said movable member to said second pedal, said train of mechanism including a lost motion connection as one of its links.

16. In a multiple pedal system for controlling the operation of an addressing machine which said system comprises a print-

ing pedal and a skip pedal, the combination, with said above recited apparatus, of a power disconnecting device normally tending to go into action, a chain of mechanism including a detachable connection, which chain of mechanism extends from said device to said skip pedal, transmits motion

from the latter to the former and is adapted to hold said device out of operation while said skip pedal is depressed, and automatic 10 means for breaking said connection.
